Kathleen Cohen
ATTORNEY

UNITED STATES PATENT OFFICE.

EDWARD SPINGARN, OF BROOKLYN, NEW YORK.

NEGLIGÉE COLLAR.

1,294,843.

Specification of Letters Patent. Patented Feb. 18, 1919.

Application filed November 23, 1916. Serial No. 132,962.

To all whom it may concern:

Be it known that I, EDWARD SPINGARN, a citizen of the United States, and a resident of New York city, borough of Brooklyn, in the county of Kings and State of New York, have invented certain new and useful Improvements in Negligée Collars, of which the following is a specification.

This invention relates to negligée or soft 10 collars and has for its principal object to provide simple and inexpensive means whereby the collar may be stiffened at those portions where it wrinkles in the ordinary course of wear.

Hitherto this wrinkling of the collar has been a serious objection and has tended to prevent a more general use of this type of collar that its many good qualities deserve.

My invention eliminates this objectionable 20 feature without detracting in any way from the comfort of the wearer. The collar is stiffened only at such points where my experiments have shown would eliminate the wrinkling, leaving the rest of the collar soft 25 and flexible so as not to interfere with the comfort of the wearer.

A further object of my invention is to provide a stiffening means which is readily removed when the collar is to be laundered 30 and does not add but slightly to the expense in the making up of the collar.

A further object is to provide a form of 35 stiffening member which may be easily inserted and when placed in position is securely held.

The various further objects and advantages will more fully appear from the detailed description and the features of novelty will be particularly pointed out in the 40 claims.

In the drawing illustrating the preferred embodiments of the invention,

Figure 1 is a perspective view of a negligée collar with the improved stiffening 45 means applied thereto.

Fig. 2 is a fragmental detail view illustrating the manner in which the stiffening member is inserted.

Fig. 3 is a fragmental detail view similar 50 to Fig. 2 illustrating the stiffening member in position.

Fig. 4 is a sectional view, the section being taken along line 4—4 of Fig. 1.

Fig. 5 is a fragmental detail view illustrating a modified form of stiffening member.

Fig. 6 is a similar view illustrating a further modified form of stiffening member.

Referring in detail to the drawing, the soft or negligée collar is made in the usual way with the collar portion 10 and the band portion 11, having the usual plies 12 and 13. At the lower seam 14 of the band adjacent the front, a portion of the collar seam is interrupted to provide two openings 65 or slits 15, opening into pockets, thus formed between the plies 12 and 13. A stiffening member 16 may be inserted through the openings 15 so as to properly reinforce the collar at those portions where it usually wrinkles. This stiffening member is preferably made of some material such as celluloid, stiff rubberized fabric or the like which is sufficiently flexible and resilient.

In one form of the invention, the stiffening member 16 is formed with a body portion 17 and a long base portion 18. The height of the stiffening member is approximately equal to the length of the slit 15 so that this member may be inserted through 70 the slit as illustrated in Fig. 2, and when it is placed in position, the long base 18 retains the member in place above the opening.

In the modified form of the invention illustrated in Fig. 5, the stiffening member 85 16^a has the wings 18^a extending from the bottom thereof, and is formed at the base with the curve 19 so as to facilitate the insertion of the stiffening member. In this form the wings 18^a may be made to extend 90 longer, providing a more slender, flexible construction than in the other form of stiffening.

In the further modified form illustrated in Fig. 6, the stiffening member 16^b has a 95 trapezoidal formation, the wide base portion 18^b serving to retain the member within the pocket.

It will be understood that by reason of the flexibility of the stiffening members, they 100 will readily conform to the curvature of the neck without causing discomfort, while at the same time always stiffening the collar in proper shape.

It will be seen from the above that I have 105 provided a negligée collar which is substantially as inexpensive as the usual type of negligée collar, as in making up the collar, it is merely necessary to leave part of the seam of the band open. This does not require any extra material or labor. The stiffening member may be easily inserted and re-

2
moved and when so inserted is securely held in position. By the use of my improved stiffening means, the usual stiffening interlining may be eliminated which results in 5 a saving in the cost of manufacture.

Having thus described my invention, I claim as new and desire to secure by Letters Patent:—

1. A negligée collar comprising a band 10 portion having openings therein forming pockets adjacent the front of the collar, and removable stiffening members of a height approximately equal to the height of the band located within the pockets, the width 15 of the opening being approximately equal to the height of the stiffening member and the base of the stiffening member being wider than the width of the opening, where- 20 by the stiffening member may be inserted edgewise into the pocket and held securely in place with the base disposed over the opening.
2. A negligée collar comprising a band 25 portion having pockets formed therein ad- jacent the front of the collar, and remov-

able stiffening members adapted to be inserted into the pockets, each stiffening member comprising a narrow body portion having extensions at the base thereof to form a wide base, the stiffening member being 30 adapted to be inserted lengthwise into the pocket and turned so as to dispose the wide base over the opening of the pocket.

3. A negligée collar comprising a band portion, the lower seam thereof being inter- 35 rupted adjacent the extremities of the band toward the front of the collar, and removable stiffening members disposed between the plies of the band and insertible through the openings, said stiffening members hav- 40 ing base portions which are wider than said openings whereby each member is retained in place over the opening.

Signed at New York city, in the county of New York and State of New York, this 45 8th day of November, A. D. 1916.

EDWARD SPINGARN.
